(57) **CLAIM**

The ornamental design for a tripod and monopod combo, as shown and described.

DESCRIPTION

FIG. 1 is a front, top and left perspective view of a tripod and monopod combo showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is a front, top and left perspective view of a tripod and monopod combo with its legs in an open position;

FIG. 9 is a front view of the tripod and monopod combo of FIG. 8;

FIG. 10 is a rear view of the tripod and monopod combo of FIG. 8;

FIG. 11 is a left-side view of the tripod and monopod combo of FIG. 8;

FIG. 12 is a right-side view of the tripod and monopod combo of FIG. 8;

FIG. 13 is a top plan view of the tripod and monopod combo of FIG. 8; and,

FIG. 14 is a bottom plan view of the tripod and monopod combo of FIG. 8.

The broken lines shown in the drawings illustrate portions of the tripod and monopod combo that form no part of the claimed design.
